UNITED STATES PATENT OFFICE

ELWOOD WARREN GILBERT, OF ALLENTEWON, PENNSYLVANIA, ASSIGNOR TO L. F. GRAMMES & SONS, INC., OF ALLENTEWON, PENNSYLVANIA, A CORPORATION OF MARYLAND

DESIGN FOR A LABEL OR SIMILAR ARTICLE

Application filed September 30, 1931. Serial No. 41,272. Term of patent 14 years.

To all whom it may concern:

Be it known that I, ELWOOD WARREN GILBERT, a citizen of the United States of America, residing in Allentown, in the county of Lehigh and State of Pennsylvania, have invented a new, original, and ornamental Design for Labels or Similar Articles, of which the following is a specification, reference being had to the accompanying drawings, forming part thereof.

In the drawings:

Fig. I is a face view of a label or similar article showing my new design; and

Fig. II is a sectional view of the label or similar article taken as indicated by the arrows II-II in Fig. I.

I claim:

The ornamental design for a label or similar article, as shown.

ELWOOD WARREN GILBERT.
